[57] CLAIM

The ornamental design for an expandible compact telephone, as shown and described.

DESCRIPTION

FIG. 1 is a front top isometric view of an expandible telephone in a closed position, showing my new design; FIG. 2 is a front top isometric view of the expandible telephone in an expanded position;

FIG. 3 is a bottom isometric view of the telephone illustrated in FIG. 1;

FIG. 4 is a bottom isometric view of the telephone illustrated in FIG. 2;

FIG. 5 is a front top isometric view of a modified form of expandible telephone illustrated in FIG. 1;

FIG. 6 is a front top isometric view thereof, in an extended position;

FIG. 7 is a bottom plan view of FIG. 5;

FIG. 8 is a bottom plan view of FIG. 6;

FIG. 9 is a right side elevation in a closed position;

FIG. 10 is a right side elevation in an expanded position;

FIG. 11 is a front elevation of the telephone; and

FIG. 12 is a rear elevation thereof.
